INVENTOR

George E. Conway

UNITED STATES PATENT OFFICE.

GEORGE E. CONWAY, OF TENAFLY, NEW JERSEY.

SHINGLE AND SHINGLE CONSTRUCTION.

Application filed April 28, 1924. Serial No. 709,839.

To all whom it may concern:

Be it known that I, GEORGE E. CONWAY, a citizen of the United States, residing at Tenafly, in the county of Bergen and State of New Jersey, have invented a new and useful Improvement in Shingles and Shingle Construction, of which the following is a specification.

This invention relates to shingles and to shingle construction.

One object of the invention is the provision of a novel form of shingle whereby more weather-proof and durable outer walls and roofs may be constructed therewith.

Another object of the invention is the provision of a form of shingle which may be made equally well of various materials, as of stiff or flexible compositions, such as asbestos or wood-fibre combined with pitch, tar, rubber compounds or the like; of metal, as copper, sheet iron, zinc, etc.; or of tile. A constructional feature in the shape of the shingle permits the surfaces formed thereof to have an appearance of heaviness and substantiality, so much desired for decorative value.

Another object of the invention is the provision of a shingle which may be applied to new construction or may be applied over old or worn out shingled surfaces in a substantial, attractive and useful manner, without requiring the removal of the old shingles.

Another object of the invention is the provision of a shingle which is simple in form, easy to apply in a construction and cheap to manufacture and that, if made of flexible sheet material, may be shaped in field at time of application.

Other objects and advantages will in part be obvious and in part hereinafter pointed out.

The invention accordingly consists in the feature of construction, combination of elements and arrangement of parts which will be exemplified in the construction hereinafter described and of which the scope of application will be indicated in the following claims.

In the accompanying drawings some of the various possible embodiment of the invention are shown.

Figs. 1, 2 and 3 are perspective views of shingles formed of sheet metal, tile and com-

position, respectively, embodying the invention.

Fig. 4 is a perspective view of an anchoring lath used in one form of construction, over a shingled roof. Figs. 5, 6, 7, and 8 are perspective views of anchoring shingles, Fig. 5 being that of an ordinary roofing shingle and Figs. 6, 7 and 8 being those of special types of shingles.

Fig. 9 is a diagrammatic perspective view of shingle construction, adapted for new construction work, using either composition or metallic shingles like those shown in Figs. 1 and 3 and the anchoring shingle shown in Fig. 5.

Fig. 10 is a diagrammatic perspective view of a shingle construction, adapted for new construction work, using the shingles of the type shown in Fig. 2 and the anchoring shingle, which may be made of tile, metal or stiff composition, shown in Fig. 7.

Fig. 11 is similar to that shown in Fig. 10 except that shingles used are made of a hard composition or sheet metal, like those shown in Figs. 1 and 3, and the anchoring shingles are made of sheet metal, like one shown in Fig. 8.

Figs. 12, 13 and 14 are diagrammatic perspective views of the novel shingle, applied to surfaces already covered, and illustrate the application of the invention in forms especially adapted to cover old or worn out shingled surfaces.

Referring to the drawing, A, B, and C denote metallic, tile and composition forms of the improved outer shingle respectively, each formed of a single continuous piece of material having a body or middle section 10, a lower hooked or turned in flange portion 11 and a ledge or shouldered upper portion 12.

Shingle A may be formed of any suitable sheet metal, as copper, iron, etc., or flexible composition. The lower portion 11 being bent into shape and the upper portion 12 folded over to form the ledge as plainly shown in Fig. 1.

Shingle B may be formed of the usual roofing tile or of cementitious material and have spaced holes 13 molded therein in the upper portion as shown in Fig. 2.

Shingle C, shown in Fig. 3, may be formed of stiff or flexible composition of asbestos or wood-fibre combined with tar,

pitch, rubber or the like. If made of flexible material it may be formed substantially like sheet metal shingle A and if made of stiff material it may be formed like tile shingle B with or without holes 13, depending on nature of the composition.

E, F, G, and H are various forms of anchoring, inner or under shingles; E being of the ordinary, wedge-shape roofing type and 10 preferably made of wood or hard composition. F being a flat piece of material of uniform thickness and made of wood, metal, hard composition or tile, if made of tile or metal, it may have spaced holes (not 15 shown) formed therein to correspond to the fastened points as will hereinafter appear. G being shingle, guttershaped, with upturned tapered side edges 14 and made of tile or hard composition, if made of tile 20 may have the holes 15 formed therein as shown in Fig. 7. H is a shape similar to G, with upturned edges 14, and is made preferably of sheet metal.

D is an anchoring lath, formed of a strip 25 of material of rectangular cross section and preferably made of wood or hard composition.

Referring to Fig. 9, the shingles may be mounted in a horizontal row, in connection 30 with a roof or other structure by engaging the lower or hooked ends thereof to a first row of anchoring shingles E and thereabove a horizontal row of anchoring under shingles E are secured to supporting member 16, by nails 17, with the butts thereof projecting beyond the upper portions 12 of the outer shingles. The amount of overhanging of the butt ends of shingles E being substantially equivalent to the interior 35 depth of the turned under or hooked portion 11, and the vertical adjoining seams of shingles E are staggered with respect to the corresponding seams of the outer shingles as shown in Fig. 9. A second horizontal 40 row of outer shingles are then fastened in place by hooking the lower portion 11 of the outer shingles over the projecting butts of the shingles E. The last row of outer shingles are spaced with respect to the lower 45 row so that the vertical seams of each is substantially in alignment with the vertical center line of body portion 10 of the outer shingles. This process is repeated until the entire 50 structure is covered. Although shingle 55 E is shown in the drawing about as wide as the outer shingle it may, in actuality, be considerably narrower and extend only a short distance on each side of the vertical 60 seams of outer shingles. Fig. 9 clearly shows the improved weather proof construction in which the under shingle firmly holds in place the lower edge of the outer shingle and prevents any seepage at the adjacent 65 seams by acting as draining means. The

lower edge of the outer shingle, due to its 65 construction and shape, gives the appearance of heaviness and substantiality so much desired for decorative value.

Referring to Fig. 10, the outer shingle B and the anchoring inner shingles G are 70 mounted in the same way as described above in connection with Fig. 9. Here the inner shingles G is gutter-shaped and the upturned edges 14 of each are spaced with respect to vertical seam between outer shingles 75 as shown in Fig. 10. Since shingles B are of tile or cementitious material, spaced holes 13 are provided for fastening said shingles in place, as is well understood. Inner shingle G may be of tile, wood or hard compositions. 80

The construction shown in Fig. 11 is similar to that shown in Fig. 10 except the outer shingle may be either of hard composition or sheet metal and the inner shingle of form H, preferably of sheet metal. 85

The construction shown in Figs. 12, 13 and 14 may be used on new work but is particularly adapted for surfaces already shingled. In Fig. 12 K, K, K, denote a shingled surface. The lower horizontal row of 90 improved outer shingles are placed first as shown, then the lower anchor lath D is fastened so that it extends over the upper ends of the lower row of outer shingles. A second row of outer shingles are then hooked over the laths D and fastened as shown. This process may be continued until the entire under surface is covered. 95

In Fig. 13 the outer shingles are fastened to the shingled surface K without the use 100 of any extra inner member, the upper portion of the lower row of horizontal outer shingles being slipped under the exposed edge of the shingled surface K so that the said edge projects as shown and the second horizontal row of outer shingles is hooked to the said projecting edge. The construction 105 may be completed by repeating the process explained above. 110

Fig. 14 shows a modified form of construction using an inner anchoring shingle of uniform thickness. From the above description of the other figures and an inspection of Fig. 14 this construction can be clearly understood without further comment. 115

It will thus be seen that there is provided a shingle and shingle construction in which the several objects of this invention are achieved and which meet the condition of practical use to give unusual satisfaction. 120

As many other possible embodiments might be made to the above invention and as various changes might be made in the embodiment above set forth, it is to be understood that all matters herein set forth or shown in the accompanying drawings is to be interpreted as illustrative and not in a 125 limiting sense.

Having thus described my invention I claim as new and desire to secure by Letters Patent:

1. A shingle comprising a middle body portion, a hook portion at one end thereof adapted to engage anchoring means on the surface to be covered and a shouldered portion of substantial thickness for spacing and supporting other anchoring means on said surface. 5
2. A shingle having a middle section and two portions at the opposite ends thereof folded back on themselves to provide a hook at one end adapted to engage anchoring means on the surface to be covered and a completely closed seam of substantial thickness at other end for spacing and supporting other overlying anchoring means on said surface. 15
3. A shingle of the class described, having one edge thereof provided with a hooked flange portion inwardly extending upon one side face of said shingle adapted to engage an anchoring means on the surface to be covered and a ledge of substantial thickness provided along the opposite edge upstanding from the opposite side face of said shingle, said ledge forming an abutment for the end of the flange portion of an overlapping shingle and a support for another surface anchoring means in a shingle construction. 25
4. In a shingle construction, the combination of a plurality of shingles laid in a row, each shingle having a hooked portion at one end and an upstanding shouldered portion at the other and anchoring means on a surface to be covered for interlocking with the said hooked portions, the said shouldered portions having a plain surface substantially 30 at right angles to the mid-portion of the shingle and adapted to serve as an abutment for the edge of the hook portions of overlapping shingles and to support said anchoring means. 40
5. In a shingle construction, the combination of a plurality of shingles laid in a row, each shingle having a flat body portion with two of its opposite end portions folded back on themselves on opposite sides of the shingle to provide a hook on one end and a double thickness of material at the other end portion, and anchoring means secured to a surface to be covered for engaging with said hook, said double thickness of material 45 forming an upstanding ledge abutment for overlapping shingles and a support for said anchoring means. 50
6. In a shingle construction, the combination of a plurality of outer shingles laid in a row, each shingle having a hooked portion at one end and an upstanding shouldered portion at the other, a plurality of anchoring shingles laid in a row adapted to have their ends disposed to project over the upstanding shouldered portion of an adjoin- 55
- ing row of outer shingles, and fastening means passing through the overlaid portions of said anchoring shingles adapted to secure same to the supporting structure, said hook portions engaging with the projecting ends 60 of the anchoring shingles in an adjacent row. 70
7. In a shingle construction, the combination of a plurality of outer shingles laid in a row, each shingle having a flat body portion with two of its opposite end portions folded back on themselves on opposite sides of the shingle to provide a hook on one end and a double thickness of material at the other end portion, a plurality of inner shingles laid in a row adapted to have their ends positioned overhanging the ledges of adjoining row of outer shingles, and fastening means passing through the overlaid portions of said inner shingles adapted to secure same to the supporting structure, said hook portions interlocking with the overhanging ends of the inner shingles to anchor the outer shingles in an adjacent row. 75
8. In a shingle construction, the combination of a plurality of shingles laid in overlapped rows, each row comprising a plurality of shingles, each shingle having a hooked portion at one end and an upstanding shouldered portion at the other, and anchoring means on a surface to be covered disposed between the rows of shingles for interlocking with said hook portions, having a plain surface substantially at right angles to the mid-portion of the shingle, said shouldered portions serving as abutment for ends of the hook portions on the overlapping shingles and as a support for the anchoring means. 80
9. In a shingle construction, the combination of a plurality of shingles laid in overlapped rows, each row comprising a plurality of shingles, each shingle having a flat body portion with two of its opposite end portions folded back on themselves on the opposite sides of the shingle to provide a hook on one end and a double thickness of material at the other end portion, and anchoring means secured to a surface to be covered and extending between the rows of shingles for engaging with the said hook portions, said double thickness of material forming an upstanding ledge abutment for the ends of the hook portions of the overlapping shingles and a support for overlying anchoring means. 85
10. In a shingle construction, the combination of a plurality of outer shingles laid in overlapping rows, each row comprising a plurality of shingles, each shingle having a hooked portion at one end and an upstanding shouldered portion at the other, a plurality of anchoring shingles laid in overlapping rows and disposed between the rows of outer shingles adapted to have 90
- 110
- 115
- 120
- 125
- 130

their ends positioned to project over the up-
standing shouldered portions of adjoining
rows of outer shingles, and fastening means
passing through the overlaid portions of said
anchoring shingles adapted to secure same
to the supporting structure, the projecting
ends of the anchoring shingles engaging
with said hook portions of the outer shingles
in an adjacent row, said shouldered portions
10 serving as an abutment for the ends of the
hooked portions on the overlapping outer
shingles and a support for projecting portion
of anchoring shingles.

11. In a shingle construction, the combination
15 of a plurality of outer shingles laid
in overlapping rows, each row comprising a
plurality of shingles, each shingle having a
flat body portion with two of its opposite
end portions folded back on themselves on
20 the opposite sides of the shingle to provide
a hook on one end and a double thickness
of material at the other end portion, and a
plurality of inner shingles secured to the
construction in overlapping rows and ex-
25 tending between the rows of outer shingles
to overhang the ledges of the adjoining
rows of outer shingles, the overhanging
ends of the inner shingles interlocking with
the hook portions of outer shingles in an ad-
30 jacent row, said double thickness of material
having a plain abutment surface sub-
stantially at right angles to the said body
portion for the ends of the hook portions
of the overlapping outer shingles and form-
35 ing a support for overhanging portions of
inner shingles.

12. In a shingle construction the combination
40 of a supporting structure, rows of
overlapping inner shingles, rows of rigid
outer shingles covering the exposed surfaces
of the inner shingles and interposed between
adjacent rows of inner shingles, said outer
45 shingles having integral means for sup-
porting and spacing the free ends of the in-
ner shingles in an overhanging position to
serve as an anchoring means for other outer
shingles and fastening means passing
50 through the portion of inner shingles and
underlying portion of the outer shingle for
securing the shingles to the supporting
structure.

13. A method of constructing a shingled

surface having in combination rows of outer
shingles and rows of inner shingles inter-
posed therebetween, each outer shingle hav-
ing abutting means and interlocking means
thereon comprising in applying a plurality
55 of outer shingles, one at a time, on a sur-
face, to form a row, overlapping each outer
shingle, with an inner shingle, said inner
shingle being positioned to extend beyond
nailing in position the overlapping portions
60 of said inner shingles through the abutting
means, interlocking, one at a time, a second
row of outer shingles.

14. A method of constructing a shingled
surface having in combination rows of outer
shingles and rows of inner shingles inter-
posed there between, each outer shingle
70 having abutting and interlocking means
thereon, comprising in applying a plurality
of outer and inner shingles in overlapping
rows with the inner shingles positioned to
overlay and extend beyond the abutting
75 means on the outer shingles, fastening the
inner shingles and the underlying outer
shingles to the supporting structure and in-
terlocking a second row of outer shingles
to the inner shingles.

15. A method of constructing a shingle
surface on a structure having rows of over-
lapping anchoring shingles, comprising in
applying a row of outer shingles, each
85 having a shouldered edge portion over a
row of anchoring shingles with the said
edge portions of the outer shingles in-
serted between two adjacent rows of an-
choring shingles to support the free end
90 portions of the upper rows of anchoring
shingles in spaced relation to the underly-
ing outer rows of shingles, fastening the
rows of outer shingles in place, and apply-
ing a second row of outer shingles between
95 the next two adjacent rows of anchoring
shingles over the aforementioned upper row
of anchoring shingles to support the free
end portions of the row of anchoring shingles
overlying said second row of outer
shingles.

In testimony whereof, I, GEORGE E. CON-
WAY, have signed my name to this specifica-
tion, this 24th day of April, 1924.

GEORGE E. CONWAY.
